WASHING AND CENTRIFUGING TEXTILES

Aaron A. Loweke, Detroit, Mich., assignor, by
mesne assignments, to Bendix Home Appliances, Inc., Detroit, Mich., a corporation of
Delaware

Application May 8, 1936, Serial No. 78,692

5 Claims. (Cl. 8—159)

One of the chief difficulties encountered in the use of washing machines having a single receptacle, rotatable on a vertical axis, in which textiles are both washed and centrifuged, arises from 5 the vibration that occurs during the centrifuging operation by reason of uneven distribution of the textiles in the receptacle. The uneven distribution of the textiles at the end of the washing operation causes unbalancing of the receptacle 10 to such a degree that none of the known automatic balancing devices applicable to such washing machines are capable of bringing the receptacle back into balance.

Although the textiles can be distributed in the 15 receptacle by hand, an arrangement whereby the textiles are automatically distributed during or at the conclusion of the washing operation would obviously be a great convenience. In addition, such an arrangement would make possible the use 20 of an automatic controlling device for putting the washing machine through the washing and centrifuging operations.

The principal object of the present invention is to provide a system for the washing, automatic 25 distribution and centrifuging of textiles in a single receptacle. More specific objects and advantages are apparent from the description, in which reference is had to the accompanying drawings illustrating preferred apparatus for carrying out the 30 invention.

Figure 1 is a vertical section of a preferred apparatus for carrying out the invention;

Fig. 2 is a vertical section of the central portion 35 of the apparatus on a larger scale;

Fig. 3 is a vertical section of a modified apparatus for carrying out the invention;

Fig. 4 is a vertical section of the central portion 40 of the apparatus of Fig. 3, on a larger scale;

Fig. 5 is a fragmentary horizontal section taken 45 on the line 5—5 of Fig. 4;

Fig. 6 is a section similar to Fig. 4 showing a portion of the apparatus slightly modified;

Fig. 7 is a wiring diagram of the electrical apparatus used in the controlling of the devices illustrated in the preceding figures; and

Fig. 8 is an elevation, partly in section, of the controller used in the electrical system.

These specific drawings and the specific description that follows are to disclose and illustrate the invention and are not to impose limitations upon the claims.

An apparatus embodying the invention includes a receptacle for textiles mounted to rotate on a substantially vertical axis. In order that the automatic distribution of the textiles in the recep-

tacle may be accomplished, the apparatus is provided with a means for agitating textiles immersed in liquid in the receptacle by agitation of the liquid without propelling the textiles by nonfluid agencies. Finally, the apparatus is provided with a means for rotating the receptacle, after the distribution of the textiles has been accomplished, at a speed high enough for centrifugal extraction of a substantial quantity of liquid from the textiles.

When the apparatus is to be automatic, an automatic controlling device is provided to cause the distribution and the centrifuging to take place in succession. An arrangement for the disposal of the liquid used in the washing of the textiles may also be included in the apparatus. Since the agitation of the textiles that occurs while they are being distributed in the receptacle produces a thorough washing and scrubbing of the textiles, this agitation can be employed for the washing operation as well as for the distribution that takes place between the washing and centrifuging operations. During the washing operation, the liquid in the receptacle may be drained and replaced with fresh liquid. Thus the first liquid employed may consist of soap suds and the second liquid rinsing water, and the discharging of the wash water and supplying of the rinse water may be accomplished automatically by means of the controlling device.

In the preferred method of agitating the liquid, substantially vertical currents of liquid adjacent the axis of the receptacle and substantially vertical currents of liquid in the opposite sense, remote from the axis of the receptacle, are produced, providing a toroidal flow of the liquid and in any case the agitation of the liquid is preferably accomplished by the injection of a gas or liquid therinto. A substantially vertical central post is preferably provided in the receptacle for guiding textiles that are moving vertically adjacent the post, and the fluid for agitating the liquid in the receptacle may then be injected from the lower central portion of the receptacle radially along the bottom thereof. The fluid for injection into the receptacle preferably constitutes liquid that is withdrawn from the receptacle for reinjection therinto.

In the apparatus illustrated in Figure 1, an upright cylindrical shell 10 is mounted upon casters 11 and has an inturned flange surrounding its upper end upon which rests a cover 12. A casting 13 for the electrical controller and for the inlet water pipe 14 that leads along the side of the shell 10 is welded to the side of the shell. On

the top of the casing 13 is a circular dial marked with the operations of washing, rinsing and extracting, over which moves an indicator 15. Four radially extending brackets 16 have their outer ends riveted to the interior of the shell 10 and have their inner ends bolted to lateral supporting flanges 17 on a motor housing 18. From the lower side of the motor housing, a driving shaft 19 leads to a pump 20 supported from the motor housing by means of depending bosses 21. The motor turns and drives the pump continuously while the machine is operating.

From the bottom of a water-retaining tub 22, made of two sections welded to the interior of the shell 10, a drain pipe 23 leads to the pump 20. In the outlet pipe 24, leading from the pump to the sewer, is a solenoid valve 25 which, when energized, opens to permit the pump to withdraw the water from the tub 22. An inlet water line 26, leading from a hot water supply system, is connected through a similar solenoid valve 27 to the inlet water pipe 14. Whenever the solenoid valve 27 is open, water is supplied to the receptacle by means of an annular perforated pipe 28 connected with the inlet water pipe 14.

Projecting into the bottom of the tub 22 at the middle thereof is a supporting casting 29, which is bolted to the tub, with the interposition of a gasket 30 (see Fig. 2). Bolted to the lower edge of the supporting casting 29 is a transmission housing 31, upon which is mounted a shifting solenoid 32. The main shaft 33 of the apparatus extends upward through the transmission housing and supporting casting and has splined thereon a conical inner clutch member 34 which is shiftable by means of a yoke 35. A spring 36 normally actuates the yoke to hold the inner clutch member 34 downward and a rod 37 connected to the shifting solenoid actuates the yoke 35 in the opposite direction whenever the solenoid is energized.

Contained in the tub 22 is a rotary receptacle 38, which has a hollow central post 39 and is mounted on a base 40, resting upon a ball bearing on the top of the supporting casting 29. The base 40 has a hollow downward extension 41 surrounding the main shaft 33, to the bottom of which is screwed a conical outer clutch member 42. The supporting casting 29 has a recess extending upward thereinto, which surrounds the downward extension 41 of the base 40. A spring 43 presses a steel gasket 44 to squeeze a rubber gasket 45 into a recessed Bakelite seal ring 46, for the purpose of sealing the ring to the extension 41. The seal ring 46 bears against a machined steel washer 47, which is sealed to the top of the recess in the supporting casting by means of a rubber gasket 48.

The main shaft 33 extends through an upward extension 49 of the base 40, and at its upper extremity has a driving connection with an impeller 50 journaled upon the exterior of the upward extension 49 of the base 40. By means of four vanes 51 on the impeller, water is drawn into the hollow post 39 through perforations 52 in the upper portion thereof, and is expelled radially from the post through lower perforations 53. The impeller rotates and the receptacle remains stationary when the clutch members 42 and 34 are disengaged, and the water propelled by the impeller travels in the toroidal path indicated by the arrows in Figure 1. The currents of water flow upward along the outer wall of the receptacle and downward adjacent the central post. As a result, the textiles are distributed evenly through-

out the water. When textiles are washed in an ordinary agitator washing machine, the radial vanes of the oscillating agitator propel the clothes back and forth in the wash water and cause them to become tangled, bunched and unevenly distributed in the washing receptacle.

In contrast, textiles agitated in the apparatus illustrated in the drawings become and remain evenly distributed throughout the water, so that the receptacle may be rotated at centrifuging speed without preliminary manual distribution of the textiles in the receptacle. Perforations 54 are provided in the bottom of the receptacle to permit the draining of water therefrom, and perforations 55 are provided in the portion of the receptacle of maximum diameter, for the ejection of water by centrifugal force during rotation of the receptacle.

In the lower portion of the tub 22, there is provided an aperture below which is secured a pressure switch casing 56. The aperture between the tub 22 and the casing 56 is closed by means of a flexible diaphragm 57 responsive to the pressure of the water thereon. A switch arm 58 is mounted in the casing 56 upon a fulcrum 59 and is connected to the diaphragm 57 by means of a link 60. When the tub 22 has been filled to the desired level with water, the diaphragm 57 is flexed downward sufficiently to open the switch in the housing 56.

In the apparatus of Figure 3, the upper portion of the shell 10 constitutes the side-wall of the water-retaining tub, and the bottom of the tub is formed by a pan 61 welded to the interior of the shell 10. The transmission housing 62 of Figure 3 rests upon the motor housing 18, and the supporting casting 63 has the inlet nipple 64 of the drain pipe 23 formed integral therewith. To expedite the scrubbing of the clothes, the receptacle 65 is provided with ribs 66. The solenoid 67 for actuating the transmission is secured to a bracket 68 bolted upon the transmission housing 62.

Instead of a single conical clutch member, a member 69, (see Fig. 4) splined on the drive shaft 10 of the motor, having two opposed conical faces, is shifted by means of the yoke 35. When the member 69 is forced into its lower position by energization of the solenoid 67, it engages a female clutch member 71 on the bottom of which is formed a pinion 72. In mesh with the pinion 72 is a gear 73, fixed on an idle shaft 74. The gear 73, by means of a pinion 75 fixed on the idle shaft, drives a gear formed on the lower end of a sleeve 76. A step bearing for the sleeve 76 is provided by a machined ring 77 threaded on the exterior of the sleeve.

When the double clutch member 69 is in its normal upper position, it engages an upper female clutch member 78, which is provided with a square socket into which the main shaft 79 of the apparatus extends. A machined ring 80 threaded on the exterior of the upper female clutch member 78 provides a step bearing for that member upon an internal shoulder of the sleeve 76.

Resting on a rubber gasket 81 on top of the supporting casting 63, is a machined collar 82 which forms a sealing step bearing for a base casting 83. The base casting has a machined washer 84 keyed thereon to ride upon the collar 82. Keyed to the exterior of the base casting 83 is a vertical tube 85, which terminates at its upper end in turned-over tongues 86 to which is welded a cap 87. Welded to the lower edge of the 75

cap 87 is an outer sleeve 88 forming a central post for the receptacle, which is provided with horizontal corrugations 89 and vertical corrugations 90 (see Fig. 5) that assist in the scrubbing 5 of the textiles.

Threaded into the upper end of the main shaft 79 is a screw bolt 91 beneath which is a washer 92 retaining a spring 93 that presses against the upper end of a screw impeller 94 surrounding 10 the shaft. This impeller is slidable vertically upon the shaft and has a square socket in its upper end that fits over the squared upper end of the main shaft 79. Sealed on the main shaft 79 is a Bakelite seal ring 95 upon which the screw 15 impeller is supported by means of a spring 96. The seal ring 95 turns on the machined upper face of a steel washer 97 supported on and sealed to the base casting 83 by means of a rubber gasket 98.

20 The base casting 83 is provided with fingers on its lower side that mesh with corresponding fingers on the upper side of the sleeve 16, so that the base casting and the tube and receptacle supported thereby are driven at centrifuging speed whenever the double clutch member 69 is in engagement with the lower female clutch member 71. When the clutch member 69 is in raised position, the rotating impeller draws water into the tube 85 from the space between the 25 receptacle 65 and the pan 61, through perforations 99 in the bottom of the tube. From the top of the tube, the water passes down through the outer sleeve 88 and it is injected radially from the sleeve along the bottom of the receptacle 65. Toroidal currents in the water in the receptacle 65, about a horizontal circular axis at the centers of the circles of arrows shown in Figure 1 of the drawings, and similar to the currents in the receptacle of Fig. 1, are thereby 30 set up. The water flows upwardly adjacent to the outer walls of the receptacle 65, and downwardly adjacent to the central post of the receptacle, as indicated by the arrows in Fig. 3. In addition, some of the water drains continuously 35 through perforations 100 in the bottom of the receptacle 65 to replace the water drawn into the tube 85 by the impeller.

Figure 6 illustrates an apparatus that is constructed somewhat differently from the apparatus shown in Figure 4, but operates in exactly 40 the same manner. The base casting 101 of Fig. 6 has keyed thereto a short vertical tube 102, which rests upon an interior shoulder of the base casting. The screw impeller 103 and the main shaft 104 of Fig. 6 are considerably shorter than the impeller and main shaft of Fig. 4, and the water is discharged directly from the top of the impeller into the receptacle. A crown plate 105, supported from the bottom of the receptacle by 45 means of a spider 106, is employed to direct the water from the top of the tube 102 downward and outward along the bottom of the receptacle and to support and close the bottom of the central post 107.

50 Figure 7 illustrates the electrical control system employed in the devices of Figs. 1 and 3. Mounted upon a Bakelite base 108, forming the bottom of a controller housing 109, are concentric arcuate strips of copper 110. The controller housing 109 fits into the upper end of the casing 13 on the side of the shell 10.

A contact arm 111 is fixed upon a vertical shaft 112 and carries contacts 113 (see Fig. 8), which sweep along the upper edges of the copper strips 75 110. The vertical shaft 112 has its lower end piv-

oted upon a step bearing 114 fixed in the center of the Bakelite base 108 and is driven at a slow speed, in a clockwise direction, by an electrical motor and reduction gearing inside a casing 115 that fits in the upper end of the controller 5 housing 109. The upper end of the shaft 112 extends through a cover 116 on the top of the controller housing 109 and has fixed thereon the indicator 15, the driving connection between the reduction gearing and the shaft 112 being capable of slippage to permit the shaft 112 to be 10 rotated manually by means of the indicator 15.

The electrical system may be connected with an electrical supply line by means of a plug 117, and a lead wire 118 connects all of the contacts 113 15 on the contact arm 111 with one of the prongs of the plug 117. Connected between the copper strips 110 that are at the greatest radial distance from the vertical shaft 112 and the other prong of the plug 117, is the solenoid 119 that actuates the clutch by which the apparatus is shifted from washing operation to centrifuging operation. The solenoid drain valve is connected between this same contact prong and the second outermost copper strips 110. Between the third 20 outermost copper strips 110 and this prong are connected, in series, the inlet solenoid valve 21 and the pressure operated switch 121. The driving motor 122 and the control motor 123 are connected in parallel between this prong and the 25 inner most copper strip 110.

When the apparatus is in its inoperative condition, as it is shown in Figure 7, none of the contacts 113 is in electrical contact with a copper strip 110. It is obvious that when the contact 30 arm is moved clockwise the slight amount necessary to bring it into contact with the innermost copper strip 110, the control motor 123 will drive the contact arm 111 on around until the contact arm again reaches the inoperative 35 position illustrated in Fig. 7. Thus, the operator may put the apparatus in operation by moving the indicator 15 clockwise a slight amount, or by holding down a push button 124 connected between the innermost contact strip 110 and the contact arm 111 long enough for the inner contact on the contact arm 111 to be moved into 40 contact with the innermost strip 110, by the control motor.

The operation of the apparatus in Figure 1 50 and of the apparatus in Figure 3 is as follows:

The operator places the textiles in the receptacle together with a proper quantity of soap, which may have a bluing compound incorporated therewith. As soon as the control motor has been 55 started, the solenoid inlet valve 21 opens and causes water to be sprayed upon the textiles in the receptacle. The main driving motor 122 operates at the same time as the control motor and drives the impeller for circulating the water. 60 When the water in the receptacle has attained the proper level, the pressure switch 121 opens and causes the solenoid inlet valve 21 to close.

The washing of the textiles then proceeds, as 65 the water in the receptacle flows in the toroidal paths indicated by the arrows, about a horizontal circular axis at the centers of the circles of arrows shown in the drawings. Even though the textiles may have all been placed at one side of the receptacle, they are soon distributed evenly 70 throughout the water therein. By the time the contact arm 111 reaches the second outermost contact strip 110, the textiles have been thoroughly washed. The closing of the circuit 75

through the second outermost contact strip causes the solenoid drain valve 25 to open.

Immediately the level of liquid in the receptacle begins to fall, and the contacts in the pressure switch are closed. Thus, as soon as the liquid begins to drain from the receptacle, the solenoid inlet valve opens and causes clean water to be sprayed into the receptacle. The impeller continues to pump water until the water has nearly all been drained, while the spraying of fresh water continues. A thorough flushing of the wash water from the textiles is the result.

Eventually, the contact arm 111 reaches the outermost contact strip 110 and the receptacle begins to rotate at a moderate centrifuging speed. Since the textiles are distributed evenly around the receptacle, there is no undue vibration. For the first part of the centrifuging operation, the spraying of fresh water into the receptacle continues. Finally, the contact arm leaves the third outermost contact strip, and the centrifuging proceeds until the water has been thoroughly extracted from the textiles, the solenoid drain valve 25 remaining open. When the de-energization of the clutch solenoid 119 causes the impeller to begin rotating and causes the receptacle to stop, the drain valve simultaneously closes and the inlet valve opens.

Then the filling of the receptacle proceeds exactly as at the beginning of the washing operation, until the attainment of a proper level causes the pressure switch 121 to open the solenoid inlet valve circuit. Agitation of the textiles in the fresh water then continues until they have received a thorough rinsing. Next the drain valve opens and the flushing of the rinse water from the textiles takes place in the same manner as at the end of the washing operation. Finally, the textiles are given a thorough centrifuging with the drain valve open and the inlet valve closed. The operator may hasten the operation of the apparatus at any time by moving the indicator 15 in a clockwise direction the desired amount.

Changes in the illustrated apparatus may be made and various systems embodying the substance of the invention may be devised to meet various requirements.

I claim:

1. In an apparatus of the class described, in combination, a receptacle for textiles to be centrifuged, mounted to rotate on a substantially vertical axis, means for distributing textiles evenly throughout liquid in the receptacle by propelling them in a toroidal path solely with fluid agencies, means for holding the receptacle against rotation during the distribution of the textiles, means for withdrawing the liquid leaving the textiles uniformly distributed about the receptacle, means for rotating the receptacle at a speed high enough for centrifugal extraction of a substantial quantity of liquid from the textiles, and automatic controlling means to cause the distribution and liquid withdrawal and extraction to take place successively.

2. In an apparatus of the class described, in combination, a receptacle rotatable on a substantially vertical axis, means for cleaning and uniformly distributing textiles immersed in liquid in the receptacle by injecting fluid into the receptacle and circulating the liquid in radically arranged vertical circular paths whereby the

textiles are distributed evenly throughout the liquid, means for withdrawing the liquid and leaving the textiles uniformly distributed about the receptacle, means for holding the receptacle against rotation during the distribution of the textiles, and means for rotating the receptacle thereafter at a speed high enough for centrifugal extraction of a substantial quantity of liquid from the textiles.

3. A method of washing and centrifuging textiles in a receptacle without removal therefrom, that comprises placing the textiles in the receptacle together with a liquid, agitating the textiles by propelling them in a toroidal path solely with fluid agencies while maintaining the receptacle stationary, whereby they are distributed evenly throughout the liquid in the receptacle, then withdrawing the liquid leaving the textiles uniformly distributed about the receptacle, and thereafter rotating the receptacle on a substantially vertical axis at a speed high enough for centrifugal extraction of a substantial quantity of liquid from the textiles.

4. Cleaning apparatus comprising a receptacle adapted to serve as a centrifuge and to contain material to be cleaned, a tub in which said receptacle is mounted for rotation about a substantially vertical axis, means for injecting cleaning liquid, a drain for said tub, drive mechanism, means driven by said mechanism for circulating the liquid in a toroidal path, means for connecting said drive mechanism to the receptacle to drive it as a centrifuge, a control circuit for the liquid-injecting means including a switch having means to operate it to open the circuit when there is a predetermined quantity of liquid in the tub, circuits controlling the drain and said connecting means, and an automatic controller for operating the apparatus in a cycle (1) with the receptacle stationary and said control circuit closed and the liquid-circulating means operating thereby to wash material placed in the receptacle, (2) then to rotate the receptacle with the drain open and the control circuit open, (3) then to inject more liquid and circulate it to distribute the material uniformly in the receptacle and at the same time to rinse said material, and (4) finally to rotate the receptacle with the drain open and the control circuit open to dry the material so distributed.

5. Cleaning apparatus comprising a receptacle adapted to serve as a centrifuge and to contain material to be cleaned, a tub in which said receptacle is mounted for rotation about a substantially vertical axis, means for injecting cleaning liquid, a drain for said tub, drive mechanism, means driven by said mechanism for circulating the liquid in a toroidal path, means for connecting said drive mechanism to the receptacle to drive it as a centrifuge, a control circuit for the liquid-injecting means including a switch having means to operate it to open the circuit when there is a predetermined quantity of liquid in the tub, circuits controlling the drain and said connecting means, and an automatic controller for operating the apparatus automatically in a cycle to clean and to rinse said material and to distribute the material uniformly in the receptacle and then to drive the receptacle to centrifuge said material.

AARON A. LOWEKE.
